OTHER PUBLICATIONS

Model of Beverage Container Carrier in public use at least by May 31, 1974.

Primary Examiner—Terry A. Wallace*Attorney, Agent, or Firm*—DeWitt M. Morgan; Kevin Lynn Wildenstein[57] **CLAIM**

The ornamental design for combined food and beverage container carrier and advertiser, as shown and described.

DESCRIPTION

FIG. 1 is a top plan view of a combined food and beverage container carrier and advertiser showing my new design; FIG. 2 is a side elevation view thereof, the opposite side being a mirror image;

FIG. 3 is a front elevation view thereof, the opposite side being a mirror image;

FIG. 4 is a bottom plan view thereof; and,

FIG. 5 is a side perspective view thereof.

The cup is shown in broken lines for illustrative purposes only and forms no part of the claimed design.
